UNITED STATES PATENT OFFICE.

HENRY BRAASCH, OF LOS ANGELES, CALIFORNIA.

BALLOTING-BOX FOR FRATERNAL ORDERS.

1,063,111.

Specification of Letters Patent.

Patented May 27, 1913.

Application filed July 25, 1910. Serial No. 573,779.

To all whom it may concern:

Be it known that I, HENRY BRAASCH, a citizen of the United States, residing at Los Angeles, in the county of Los Angeles and State of California, have invented a new and useful Balloting-Box for Fraternal Orders, of which the following is a specification.

The object of this invention is to provide a simple, certain, safe and convenient balloting box by which the ballot is determined by the casting of black and white balls and in which box there is no possibility of mixing the balls or of accidentally misvoting, or of intentional fraudulent voting, and by means of which the result of the vote can be at once exposed to all the members of the lodge when the presiding officer inspects the vote.

The accompanying drawings illustrate the invention.

Figure 1 is a perspective view of the ballot box ready for voting. Parts are broken away to expose interior parts. Fig. 2 is a broken view of the box at the inspection of the vote. Fig. 3 is a plan view omitting the top of the box and the cover with the spools and ratchet wheels, and showing part of the internal mechanism set for casting a white ballot. The normal position of such mechanism is shown in dotted lines. Fig. 3^a is a fragmental plan showing the pawl at rest. Fig. 4 is a longitudinal sectional elevation mainly in section on line indicated by x^4 , Figs. 2, 3 and 5, showing the mechanism at the moment of casting a white ballot. Fig. 5 is a cross sectional elevation coaxial of the spools on line x^5 , Figs. 4 and 6. Fig. 6 is a broken side elevation of one of the spools.

The balloting box comprises a case which is formed of a floor 1, two side walls 2, 3, a rear end wall 4, a stationary front cross-bar 5, a central cross-bar 6, a hinged lid 7 and a cover 8.

In some instances the rear end of the case is formed with a movable section 9, which may be swung by hinges 10 from the back of the floor 1, so that if it is not desired to expose the vote to the members of the lodge, the vote may be inspected by the presiding officer alone.

The case may be of any suitable material

and the cover top in some instances may be made of sheet metal bent into semi-cylindrical form and provided with front and rear flanges 12 and 13, a latch 14 being pivoted by a screw 15 to the central cross-bar 6 and adapted to swing over the flange 12 to secure the cover to the rest of the case. 60 Said cover may be provided with a handle 16 by which the balloting box may be carried when the cover is latched and by which the cover may be removed when it is unlatched. 65

The lid 7 is composed of a top piece 17, and a front piece 18. The top piece 17 is provided with a transverse sight slot 19 and the front piece fits upon the top of the front cross-bar 5 to close the front of the 70 vote indicator chamber which is formed beneath the level of the lid and above the front cross-bar. Said front cross-bar may be made of two horizontal pieces 20, 21, the upper piece 21 being a metal plate and the 75 lower piece 20 being provided with two forwardly widened grooves 22, 23, to form guides to guide the forwardly extending arms 24, 25 for the spherical black and white ball vote indicators 26, 27, which indicators 80 are operable by finger pieces 28, 29, that extend below the level of the front cross-bar and that are accessible, when the lid is closed, to the fingers of the right hand of the voter inserted underneath the front 85 stationary bar 5.

The finger pieces 28, 29, are normally held retracted by resilient means in the form of a spring 30 made of a wire bent into W form. The center loop 31 of the W 90 spring is fastened by a screw 32 to a standard 33 which supports the black and white ball arms 24, 25, a switch pawl 34, and a pin 35. A strap 36 on the standard 33 extends over the indicator arms 24, 25, to secure them in place and to allow each to slide freely forward upon the manipulation of its finger piece, and backward responsive to the pressure of the spring. The ends of said spring extend up through the finger 100 pieces and arms and project upward above the same to receive the black and white ball vote indicators 26, 27, thus securing said indicators in fixed relation to the finger pieces and the black and white ball indicator arms, respectively. 105

The switch pawl 34 has a forward central point 37 that normally stands directly behind the switch pin 35. The voting arms 24, 25, are pivoted at opposite sides of the 5 mid-length of the switch pawl, by pivots 38, to the switch pawl 34. Side posts 39 set in the standard 33 prevent the arms 24, 25 from moving too far laterally.

When either vote indicator is moved forward by its finger piece, the switch pawl will be held by one of the pivots 38 and will rotate on said pivot to move the forward point 37 to that side of the pin 35 which is away from the arm that is being actuated; 10 and the rear portion of the switch pawl will swing toward that side of the box in which the actuated arm is located. The switch pin 35 is engaged by the pawl as shown in Fig. 3 to cause the pawl to be shifted upon 15 the actuation of the finger-pieces.

The black and white ball spools 40, 41, are carried by a shaft 42, which is mounted in the frame 43 that is fastened to the under side of the cover 8. The shaft 42 may be an 20 ordinary stove bolt inserted through the frame and having the tension adjusting nut 44. The shaft may also have a spacer 45 surrounding the bolt between the nut and the bolt head. Tension springs 46 are arranged between the spools and the head and 25 nut of the bolt, respectively, so that when the nut is tightened said springs press the spools against the frame, thus to produce sufficient friction to prevent spinning of 30 the spools. The bolt freely slides through the spacer and the spacer prevents screwing 35 the nut too tight.

The spools may be constructed as shown, of a central body 47 and inner and outer 40 spool plates 48, 49. The inner spool plates 48 are formed with ratchet teeth 50 to be engaged by the switch pawl 34, and the parts are so arranged that when the switch 45 pawl is shifted by the operation of one of the finger pieces it will swing into a notch of the spool plate pertaining to such finger piece. A rock shaft 51 is journaled on the standard 33 and is provided with a cam 52 underneath the switch pawl 34 and is provided with an external handle 53 outside the 50 box and is so arranged that when the handle 53 is manipulated the switch pawl will be raised.

The switch pawl is provided with notches 55 54 to allow the pawl to escape the teeth of the spools when the pawl is in normal position.

When the switch pawl is shifted by the movement of one of the finger pieces the 60 pawl will enter between two of the teeth of the spool; and thereupon the handle may be manipulated to operate the cam and raise the switch pawl, thereby rotating the spool the space of one tooth.

65 A guard 55 for the handle 53 outside the

box determines the amplitude of the movement of the handle and prevents the pawl from being moved too far. The rock shaft is provided with an arm 56 to actuate a spring hammer 57 of a bell 58 at an appropriate time after the movement of the handle 53 has begun; so that the operation effected by moving the handle forward while one of the finger pieces is held forward by the voter, is to lift the switch pawl, thereby 70 rotating the appropriate voting spool and ringing the bell. The constructor may relatively position the lever and arm 56 and hammer 57 so as to ring the bell at any point during the stroke of the lever. 75

When the finger pieces are both free, the switch pawl is held centrally by the black and white ball indicator arms 24, 25, and will not engage either of the voting 80 spool ratchet wheels and consequently the handle may then be operated to ring the bell without moving either of the voting spools. The arms 24, 25, are resilient and form springs that may be bent up as the 85 pawl is raised, and will serve to return the switch pawl to normal position when the handle is thrown back into normal position. 90

The rock shaft may be made of a piece of wire bent at one end to form the arm 56 and bent into an intermediate loop to form 95 the cam 52 bent exteriorly to form the handle 53 which may be provided with a knob 59.

The orifices 60 in the side of the box to allow the rock shaft 51 to be inserted may 100 be large enough to admit the rock shaft by turning the same appropriately for this purpose, and the standard 33 may be provided in its top with a notch 61 to accommodate the shaft, and said shaft may be secured to the standard by bearings 62, 63, which may be fastened to the standard in any suitable way, as by screws 64.

The hammer 57 may be a wire bent to form an intermediate loop 65, and said hammer is fixed to the case by any suitable means as by screws 66 screwed into the standard near the base thereof, thus bringing the loop 65 behind the arm 56 when the handle is retracted to normal position and allowing the arm to escape the finger formed by the loop at the middle of the actuating movement of the handle as shown in dotted lines, Fig. 4 and allowing the arm to pass the finger when the handle is retracted to 110 normal position. The bell 58 may be fastened to the side of the case in any suitable manner, and is so positioned that when the hammer is released by the arm passing the finger it will strike the bell. 115

Upon each of the spools 40 and 41 is wound a string of voting balls, the left hand spool 40 being provided with a string of black balls and the right hand string 41 being provided with a string of white balls. 120 125

The strings are fastened at one end to their respective spools and the frame 43 is provided with orifices 68 vertically below the rear sides of the spools, respectively, so that 5 as a spool is unwound, a string and a ball on the string will move downward through an orifice.

On the free ends of the strings 69, 70, respectively, are large terminal balls 71, 72, 10 that are of greater diameter than the width of the orifices through which the strings extend so that they cannot be drawn up through the orifices and therefore form stops to prevent too great winding movement of 15 the spools.

The strings may be flexible connections of any desired construction or material, and along said strings there are arranged at intervals corresponding to the spaces between 20 the teeth of the spools, voting balls 73, 74; the voting balls 73 on the black side being black, and the voting balls on the white side being white. The outer plates 49 of the spools may be stamped and struck up to 25 form two diametrically opposite outwardly projecting wings 75, 76, to serve as finger pieces by which the spools may be rotated for the purpose of winding the strings of 30 balls.

The shanks 77, 78, of the finger pieces 28 and 29 may be fastened to the black and white ball arms 24, 25, respectively, by any suitable means as the rivets 79 and 80, and 35 said arms, shanks, rivets and finger pieces may be appropriately colored to assist the voter in determining what vote he is effecting.

In order to avoid confusing the voter, the shank and arm pertaining to the black ball 40 side is white and the shank and arm pertaining to the white ball side is black, so that when the voter looks down through the slot he will note a white shank on the black ball side and a black shank on the white ball 45 side. Then, in case he deems the candidate a right person to be elected he will advance the right finger piece, thus bringing the white ball vote indicator 27 into view through the slot and at the same time with- 50 drawing the black shank from view so that there will only be exposed the white shank and the white ball vote indicator, thus assuring him that he is voting the white ball. Thereupon he will manipulate the voting 55 handle thereby operating the mechanism to unwind one white ball from the white ball spool. If, however, he deems the candidate an unfit person and one who should be left outside the lodge, he will pull forward the 60 left finger piece, thus moving the white shank out of sight and the black ball vote in- 65 dicator 25 into sight through the slot so that as he looks through the slot he will see only the black ball indicator and the black shank of the white ball indicator, thus assuring

him that he is about to cast a black ball ballot. Thereupon he will manipulate the handle and thus actuate the mechanism to unwind one black ball from the spool.

It is the rule in lodges to exclude any 70 candidate who receives a limited number, say two or three, black balls, so that it is not necessary in order to exclude a member that there shall be a large number of black balls provided, and it is only necessary, 75 therefore, in inspecting the ballot to determine whether a number of black balls has been voted sufficient to exclude the candidate. It is desirable, however, that a requisite number of votes be noted in order to give 80 concealment to the personality of the members voting the black balls, and this is effected without the necessity of voting a white ball by every member who votes favorable. Therefore, the proper balloting 85 may be effected by providing the spools with a limited number of balls, say twenty-five, more or less, for each string, and a corresponding number of ratchet teeth may be provided on each spool; and at the spaces 90 which come adjacent the switch pawl after the last ball has been lowered through the frame, an extra wide notch 81 will be provided so that the pawl when actuated will no longer actuate the spool, and therefore, 95 the strings cannot be again wound up until the spools are withdrawn from the case for that purpose.

The voters are able to alternatively actuate the affirmative or negative balloting 100 mechanism so long as the requirements of the balloting demand such actuation and when the purpose for which the balloting is being had is thus effected the balloting may, to all appearances, be continued in the same 105 manner indefinitely.

When the voting has been finished and the ballot box is placed in the possession of the presiding officer, if it is desired that the vote shall be inspected by the lodge, the 110 presiding officer will unlatch the cover and withdraw the frame with its spools thereon from the case and by inspecting the de- 115 pending balls the vote is at once apparent to all.

In case it is desired that the presiding officer alone shall inspect the vote or that the members in the lodge room shall not receive the announcement of how many black balls have been cast, the presiding 120 officer may open the rear end of the case and thus privately inspect the result of the vote. When it is desired to return the ballot box to its initial position, this is readily done by withdrawing the frame far 125 enough to allow the thumb piece of the spools to be manipulated to wind the spools, thus at once restoring the box to voting condition and thereby saving all confusion and liability of error in replacing the balls. 130

It is understood that the strings are non-stretchable; that the bodies are fixed at regular intervals therealong; that the bodies may be of any desired color and form; those of one string being differentiated in any suitable way from those of the other string; and that cubes or other bodies may be used in place of the spherical bodies without any change in the construction of the spools or other parts.

10 I claim:—

1. A ballot box provided with two strings; balloting members strung on said strings and flexibly connected thereby, the balloting members of one string being differentiated from those on the other string, and means whereby the balloting members may be moved into position to indicate a vote cast.

15 2. A ballot box comprising two spools, strings on the spools respectively, balloting members strung on one of said strings, balloting members strung on the other of said strings, and means to rotate the spools alternatively to indicate the vote.

20 3. A ballot box comprising two spools, strings on the spools respectively, balloting members strung on one of said strings, balloting members strung on the other of said strings, means to rotate the spools alternatively to indicate the vote, said means being

25 operable only by the manipulation of two elements, one of which is concealed and the other exposed to view.

4. A ballot box comprising two spools, strings on the spools respectively, balloting members strung on one of said strings, balloting members strung on the other of said strings, means to rotate the spools alternatively to indicate the vote, said means being

30 operable only by the manipulation of two elements, one of which is concealed and the other exposed to view; one of said elements being a concealed finger piece and the other element being an exposed handle.

45 5. A ballot box comprising a case provided with an opening through which the fingers of the voter may be inserted, strings inside the case, balloting members strung on one of said strings, balloting members strung on the other of said strings, a handle, finger pieces, one for each of said strings and means between the finger pieces and the strings whereby the manipulation of the finger pieces in conjunction with the operation 50 of the handle will move one of the strings to effect the casting of the vote.

60 6. A ballot box comprising a case, a frame removable from the case, strings of balloting members adapted to depend from the frame to indicate the vote cast, and mechanism in the case to actuate the vote-indicating mechanism.

65 7. A ballot box comprising a case and a frame removable from the case, vote-indicating mechanism carried by the frame and ca-

pable of being exhibited when the frame is removed from the case, mechanism in the case to actuate the vote-indicating mechanism, said actuating mechanism comprising means to be actuated by the fingers of one of one string being differentiated in any hand and means to be actuated by the other hand; simultaneous manipulation of both said means being necessary in order to actuate the vote-indicating mechanism.

75 8. The combination with two spools, of ratchet wheels on the spools, strings of flexibly connected balloting members on the spools, a pawl, arms pivoted to the pawl on opposite sides of the mid-line thereof, means to actuate the arms independently of each other and a pin to be engaged by the pawl to cause the pawl to be shifted upon the actuation of either finger piece.

80 9. A ballot box, two strings, balloting members strung on one of said strings, balloting members strung on the other of said strings, the balloting members of one string being differentiated from those of the other string, means whereby the balloting members may be alternatively moved into position to indicate a vote cast, means to conceal the balloting members, and means to withdraw the balloting members from concealment.

90 10. A ballot box, two strings, balloting members strung on one of said strings, balloting members strung on the other of said strings, the balloting members of one string being differentiated from those of the other string, means whereby the balloting members may be alternatively moved into position to indicate a vote cast, means to conceal the balloting members, means to withdraw the balloting members from concealment, and means to wind up the strings when said balloting members are withdrawn from the concealing means.

100 11. A ballot box, two strings, balloting members strung on one of said strings, balloting members strung on the other of said strings, the balloting members of one string being differentiated from those of the other string, means including concealed finger pieces and an exposed handle whereby the balloting members may be alternatively moved into position to indicate a vote cast, means to conceal the balloting members, and means to withdraw the balloting members from concealment.

110 12. A ballot box comprising two spools, strings on the spools respectively, balloting members strung on one of said strings, balloting members strung on the other of said strings, and pawl and ratchet means to rotate the spools alternately to indicate the vote.

115 13. A ballot box comprising two spools, strings on the spools respectively, balloting members strung on one of said strings, balloting members strung on the other of said strings,

strings, and pawl and ratchet means to rotate the spools alternatively to indicate the vote; there being concealed finger pieces and an exposed lever to actuate the pawl and ratchet means.

14. In a ballot box, a standard, spools provided with strings of balloting members and also provided with ratchet teeth, a switch pin, a pawl on the standard, said pawl having a forwardly central point, resilient arms pivoted to the pawl on opposite sides of the middle line thereof, said pawl terminating at the point between said arms, springs to actuate the arms to hold the pawl in normal position with its point directly behind the pin, finger pieces to actuate the arms alternatively to engage the pin, thus to shift the pawl into position to engage the ratchet

wheels alternatively, and means to raise the pawl when so shifted. 20

15. A balloting box comprising a case provided with a slot, vote indicating means, mechanism in the case for actuating the vote indicating means, and vote indicators connected with said mechanism and adapted to be alternately brought into view beneath the slot to indicate to the voter the character of the vote being cast. 25

In testimony whereof, I have hereunto set my hand at Los Angeles, California, this 9th day of July, 1910. 30

HENRY BRAASCH.

In presence of—

JAMES R. TOWNSEND,
OLIVE DIFFENDERFER.

Washington, D. C."

Correction in Letters Patent No. 1,063,111.

It is hereby certified that in Letters Patent No. 1,063,111, granted May 27, 1913, upon the application of Henry Braasch, of Los Angeles, California, for an improvement in "Balloting-Boxes for Fraternal Orders," an error appears in the printed specification requiring correction as follows: Page 4, strike out line 71; and that the said Letters Patent should be read with this correction therein that the same may conform to the record of the case in the Patent Office.

Signed and sealed this 12th day of August, A. D., 1913.

[SEAL.]

E. B. MOORE,

Commissioner of Patents.
